GALVANIZING APPARATUS

Karl Merkenschlager, Nuremberg, Germany

Application January 5, 1934, Serial No. 705,388
In Germany March 18, 1932

3 Claims. (Cl. 204—11)

My present invention relates to a galvanizing apparatus for producing electro-deposits, especially electro-deposits of chromium.

According to my invention the galvanizing apparatus is constructed in such a manner, that a perforated basket is situated within the rotating drum receiving the electrolyte, which is rotatably connected to the drum. By this arrangement a steadiness is created within the electrolyte, since the latter and the drum are simultaneously rotating. Therefore the current lines can not be interrupted by the perforated basket and thus a continued surface-contact for the current lines is assured. Also the speed of rotation may be increased as required without interruption of the current lines. Further owing to the increased speed of rotation the centrifugal force may be suited to the weight of the articles to be galvanized, so that additional powers for proper distribution of the articles within the drum are not necessary. Owing to this fact articles made of other metals than iron may be galvanized.

A further improvement of the galvanizing apparatus is that the basket may be made of insulating material and closely perforated. The holes are less than 1,5 mm. in diameter and the current conductors are sunk so far within the walls of the basket, that they project only a very little.

A further improvement is the arrangement of a second basket within the first basket receiving the articles and being also rotated. This second basket consists of elastic and fine-meshed wire netting and has the purpose to hold the introduced articles in position between the two baskets, when pressed against the first basket.

The accompanying drawing shows by way of example the invention, in which

Fig. 1 is a longitudinal section and

Fig. 2 a partly taken section of an improved execution of the apparatus.

The bath drum *a* receiving the electrolyte is journaled on an axis *b* which is rotated by means of a tooth gear *c* in known manner. Within this drum is situated a perforated and funnel-shaped basket *d*, which is rotatably connected with the drum and serves to receive the articles to be galvanized. On both sides of the basket *d* are placed the internal-anode *e* and the external-anode *f* into which the current is sent in known manner by means of slip rings. The rotatable drum is surrounded by a case *g* which catches the distributed bath solution and is provided at the top with an accumulating pipe *h* for the purpose to let escape the gases produced within the drum during the galvanizing process.

The said basket *d* may also be made of insulat-

ing material and provided with very small holes, the diameter of which is less than 1,5 mm. Thereby the current conductors are sunk so far within the wall of the basket, that they project only a very little.

According to Fig. 2 of the drawing a further basket *i* is arranged concentrically to the first basket *d*, which is also perforated and carries the current conductors on both its sides. By this basket so constructed the articles distributed upon the inner surface of the first basket *d* are pressed firmly down, this is obtained by weighted levers, which engage with a collar bearing *k* connected with the basket *i*. On both outsides of the surfaces of the baskets *d* and *i* the external and internal anodes *l* and *m* are arranged, by means of which the current is sent over the slip rings and contacts. The rotating drum *a* is surrounded by a fixed spray-case *n*, which carries a drain cock leading to a container adapted to receive the drained bath solution.

Naturally the described apparatus not only serves for electro-depositing chromium, but can also be used for other deposits.

What I claim is:

1. A galvanizing apparatus consisting of a rotating drum receiving the electrolyte, comprising in combination a perforated and funnel-shaped basket placed within said drum and connected rotatably with the latter, a second funnel-shaped basket situated concentrically within said first basket and connected rotatably with the latter, external and internal anodes placed on both sides of both the baskets within said drum and connected rotatably with the latter.

2. A galvanizing apparatus consisting of a rotating drum receiving the electrolyte, comprising in combination a perforated and funnel-shaped basket placed within said drum and connected rotatably with the latter, a second funnel-shaped basket situated concentrically within said first basket and connected rotatably with the latter, external and internal anodes placed on both sides of both said baskets within the drum, a collar bearing arranged on the second basket, weighted levers adapted to engage with said collar.

3. A galvanizing apparatus consisting of a rotating drum receiving the electrolyte, comprising in combination a perforated and funnel-shaped basket placed within said drum, a second funnel-shaped basket situated concentrically within said first basket and made of elastic and fine-meshed wire netting, external and internal anodes placed on both sides of both said baskets within the drum and connected rotatably with the latter.

KARL MERKENSCHLAGER.
